Primary Examiner—Wallace R. Burke*Assistant Examiner*—Marcus Jackson*Attorney, Agent, or Firm*—Morton J. Rosenberg; David I. Klein**[57] CLAIM**

The ornamental design for a combined earthquake warning and indicator anti-theft clock, as shown and described.

DESCRIPTION

FIG. 1 is a perspective view of a combined earthquake warning indicator and antitheft clock showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

FIG. 1

FIG. 2

FIG. 3

FIG. 4

FIG. 5

FIG. 6

FIG. 7
